UNITED STATES PATENT OFFICE.

EDWIN F. BEUGLER, OF BUFFALO, NEW YORK, ASSIGNOR TO E. & B. HOLMES MACHINERY CO., OF BUFFALO, NEW YORK, A CORPORATION OF NEW YORK.

VARIABLE-SPEED COUNTER-SHAFT.

1,127,166.

Specification of Letters Patent.

Patented Feb. 2, 1915.

Application filed March 13, 1913. Serial No. 753,988.

To all whom it may concern:

Be it known that I, EDWIN F. BEUGLER, a citizen of the United States, residing at Buffalo, in the county of Erie and State of New York, have invented certain new and useful Improvements in Variable-Speed Counter-Shafts, of which the following is a specification.

The invention relates generally to improvements in variable speed counter-shafts, and more particularly to a structure in which the power from the driving element is transmitted to the driven element through a plurality of simultaneously controlled friction elements.

The main object of the present invention is the provision of a variable speed counter-shaft embodying duplicate simultaneously operated friction disks, the movement of the friction disks with relation to the adjacent disks coöperating therewith inducing the desired variation in speed and being manually controlled through a simple, effective mechanism.

A further object is the provision of means for manually controlling the coöperation of the driving friction disk with the adjacent friction disk, whereby to readily govern the starting and stopping of the variable speed mechanism.

The invention in its preferred form of details will be described in the following specification, reference being had particularly to the accompanying drawings, in which:

Figure 1 is a view in elevation partly in section illustrating the improvement. Fig. 2 is a bottom plan of the same. Fig. 3 is an end elevation view from the driven end. Fig. 4 is an end elevation view from the driving end. Fig. 5 is an enlarged section, partly in elevation illustrating the manually operated control means for the friction disk. Fig. 6 is a broken section partly in elevation through such control means, taken at right angles to the section of Fig. 5.

Referring particularly to the accompanying drawings, wherein the improved variable speed counter-shaft is shown as an overhead shaft, the details comprehend a hanger 1 including a ceiling plate 2 of appropriate size and strength designed to be bolted or otherwise secured to the overhead support 3. Supporting beams 4 depend from the plate 2 and are formed with or

otherwise constructed to provide shaft bearings 5 at their lower ends. The beams 4 are connected by an intermediate strut 6 in parallelism with the ceiling plate and connected thereto by a web 7, a supporting beam 8 depending centrally from the strut and terminating on a plane above the bearing 5. The beams 4 are provided with outwardly and downwardly extending arms 9 and 10, the former of which in line with the bearing 5 is formed to provide a bearing 11 and extended below said bearing for a short distance and terminally provided with an interiorly threaded sleeve 12, while the arm 10 terminates in a bearing 13 in line with the bearing 5.

The framework just described is preferably of integral construction and the various parts thereof, in so far as possible, constructed of channel or angle formation to provide the requisite strength.

The driving shaft 14 is mounted in the bearing 5 of the beam 4 adjacent the arm 9, the opposite end of the shaft being mounted in the sleeve 15 supported in the bearing 11 and keyed to the shaft to prevent independent longitudinal movement of the sleeve and shaft while permitting their independent rotary movement. Keyed upon the driven shaft 14 is the driving pulley 16, said pulley being preferably arranged intermediate the bearings 5 and 11 and operated from any suitable source of power through a belt 17. Secured upon the relatively inner end of the driving shaft 14 is a friction disk 18, said disk operating in a plane located inwardly of the adjacent beam 4.

Secured upon the outer terminal of the sleeve 15 is a block 19, the transverse dimension of which exceeds the diameter of the sleeve, the inner edges of the block beyond the sleeve being each provided with a projection 20. In advance of the projection 20, and in line therewith the sleeve is provided with a diametrically extended pin 21, the ends of which extend beyond the surface of the sleeve.

Pivotedly mounted upon a lug 22 extending from the arm 9 above the bearing 13 is the manually operable control lever 23. This lever includes spaced arms 24 connected at their upper ends to provide a bearing plate 25, the arms extending on opposite sides of the sleeve and lying be-

between the projections 20 and pin 21. Immediately below the projection 20 the arms are deflected laterally and then depend in parallelism with the extension of the arm 9 below the bearing, the lower ends of the arms being formed to provide guide eyes 26. A pressure rod 27 is slidably mounted in the horizontal portion of the arm 9 and in the beam 4, bearing blocks 28 being provided for the purpose. An extension spring 29 is coiled about the pressure rod bearing between one of the blocks 28 and a stop 30 adjustably secured upon the rod 27. The outer end of the rod bears at all times against the plate 25 of the control lever 23 under the action of the spring 29.

Threaded in the sleeve 12 is an adjusting rod 31 which on the end adjacent the arms of the lever 23 is provided with a 20 chain wheel 32, an endless operating chain coöperating with said wheel for turning the same and thereby adjusting the rod 31 lengthwise the sleeve 12. The operating chain 33 passes through the respective guide eyes 26 of the lever, and the end of the rod immediately beyond the wheel 32 bears against a cross bar 34 of the lever.

The construction at the driven end of the mechanism is practically identical with that 30 described omitting the manual control, that is to say, the driven shaft 35 is mounted in the bearings 5 and 13, being provided intermediate their bearings with a driven pulley 36 from which power is taken by a belt 37. 35 The relatively inner end of the driven shaft is provided with a friction disk 38 similar to and in alinement with the driven friction disk 18. The driven shaft is mounted at its outer end in a sleeve 39 keyed to the shaft to 40 prevent independent longitudinal movement while permitting independent rotary movement. The outer end of the sleeve is provided with a block 40, similar to the block 19 at the driving end, said block having projections 41 in line with the projecting ends of a pin 42 passed through the sleeve. An automatic control lever 43 is pivoted upon a lug 44 projecting from the arm 10, the lower end of the lever, which as described in connection with the manually operated control lever includes spaced arms, being positioned intermediate the projections 41 and pin 42, while the upper end loosely receives a threaded pin 45 bearing at its inner end 55 against the block 46 secured to the arm 10 and provided at its outer end with an operating head 47, and further provided with a lock nut 48 designed to bear against the end of the lever. The threaded connection between the rod 45 and lever provides for setting the driving shaft to at all times maintain operative engagement between the friction disk 38 and the adjacent friction disk as will presently appear.

60 65 The friction mechanism through the oper-

ation of which the variable speed of the driven shaft from the fixed speed of the driving shaft is obtained, is arranged intermediate the driving friction disk 18 and the driven friction disk 38. The friction mechanism includes a block 49 having upstanding undercut edge flanges 50 adapted to co-operate with complementary formed edges 51 of a bed plate 52 supported by the hanger beam 8 and extending at right angles to the plane of the driving and driven shafts. One of the flanges 50 is preferably provided with an adjustable wear plate 53 between it and the adjacent edge of the bed plate 52 whereby to take up wear of the parts and insure an even sliding movement of the block 49 on the bed plate. The block is formed to provide a depending bearing 54, of any desired construction in which is supported what may be termed a clutch shaft 55. This shaft is arranged at a slight angle to the plane of the driving and driven shaft, for a purpose which will presently appear. The respective ends of the clutch shaft beyond the bearing 54 is provided with friction disks 56, each comprising annular wheel like sections having outstanding undercut edge flanges 57. An annular section 58 of appropriate material for friction clutch purposes is secured against the outer surface of the wheel, bearing against the flange 57 and removably fixed in place by an annular holding member 59 secured to the wheel by screw bolts 60 and bearing against the relatively inner inclined edge 61 of the clutch member 58.

The block 49 is provided with an upstanding abutment 62 having a threaded bore extending longitudinally thereof as at 63, the abutment working in an appropriately formed channel 64 provided in the bed plate 52. An adjusting shaft 65 is mounted in the bed plate for independent rotary movement though fixed against longitudinal movement. This shaft operates in 110 the channel 64 and is threaded for co-operation with the bore 63 of the abutment 62. One end of the shaft 65 projects beyond the bed plate and is provided with a chain wheel 66 with which an endless operating chain 67 115 coöperates, said chain preferably passing through eyes of a guide member 68 hung upon the shaft.

Through the angular arrangement of the clutch shaft hereinbefore referred to it will 120 be obvious that the friction disks are angularly disposed with relation to the respective friction disks, whereby the respective friction disks coöperate at diametrically opposed points, as will be noted from Fig. 2, 125 thus securing a balanced action in operation.

In use the driven friction disk 38 is adjusted through the medium of the lever 43 and set so as to remain at all times in fric- 130

tional coöperation with the adjacent friction disk 56. The driving friction disk 18 is normally maintained in coöperation with the adjacent friction disk through movement 5 of the lever 23 under the influence of the spring 29, and if at any time it is desired to interrupt this connection, such result is readily obtained by properly operating the chain 33 to move the rod 31 laterally and thereby force the lower end of the lever 23 outwardly with the effect to move the friction disk 18 out of engagement with the adjacent friction disk.

To give the desired speed, and control the 15 variation of speed the friction disks 56 are adjusted to and from the center of the friction disk, this adjustment being accomplished by operation of the chain 67 to turn the shaft 65 and move the block 49 longitudinally of the bed plate.

What is claimed is:—

1. A variable speed counter-shaft includ-
ing a driving shaft, a friction disk carried

thereby, a driven shaft, a friction disk carried thereby, friction mechanism arranged 25 intermediate the respective friction disks, means for normally setting the driven shaft to maintain contact between the friction mechanism and friction disk carried by said shaft, and manually operable means for adjusting the driving shaft to control the co-operation of its friction disk and the friction mechanism.

2. An adjusting means for controlling the 35 coöperation of clutch elements of a variable speed counter-shaft, including a driving shaft, a lever pivoted beyond the shaft, projections carried by the shaft between which the lever is located, a fixture, a rod having threaded connection with said fixture and bearing against the lever, and means for turning the rod.
